UNITED STATES PATENT OFFICE.

WILLARD G. RICH, OF ROCHESTER, NEW YORK, ASSIGNOR TO THE H. B. SMITH MACHINE COMPANY, OF SMITHVILLE, NEW JERSEY.

VELOCIPED.

SPECIFICATION forming part of Letters Patent No. 350,995, dated October 19, 1886.

Application filed October 17, 1885. Renewed September 13, 1886. Serial No. 213,461. (No model.)

To all whom it may concern:

Be it known that I, WILLARD G. RICH, of Rochester, in the county of Monroe and State of New York, have invented certain Improvements in Bicycles, Tricycles, &c., of which the following is a specification.

This invention relates to those bicycles and tricycles in which the driving-wheel is turned through the medium of clutch mechanism from alternately-acting drums mounted loosely on its axle and rotated by straps connecting with the pedals or foot-levers. As these machines are most commonly constructed, a spring is mounted in each drum to turn it backward and lift the adjacent pedal independently of the other. This construction is attended with serious troubles, among which are the frequent breakage of the springs, rendering the driving devices on one side inoperative, the weakening or settling of the springs, so that they fail to lift the pedal to the proper height, the waste of power in overcoming the springs to depress the pedal, and in lifting the limb by muscular power after each downstroke, and, more serious than any of the others, the fact that the weight of the rider is carried largely and sometimes wholly in the saddle, instead of on the pedals, the result of which is great fatigue and the transmission of injurious vibrations to the base of the spine and the gluteal regions,

The first part of my invention is directed to overcome these evils; and it consists in a peculiar manner of connecting the drums with each other and with the pedals by cords or equivalent flexible connections, as hereinafter fully explained, whereby the rotation of the drums is rendered positive in both directions, and the depression of each pedal caused to effect the elevation of the other in order that the weight of each lever will be counterbalanced by that of the other.

The invention further consists in various minor details relating to the above connections, to an improved clutch mechanism, and to other details, to be hereinafter fully explained.

Referring to the accompanying drawings, Figure 1 represents a side elevation of a bicycle of the well-known "Star" type having my improvements applied thereto. Fig. 2 is a side elevation of a machine of the facile type provided with my improvements. Fig. 3 is an eleva-

tion of one of the drums, showing the manner in which the cords are connected thereto and to the pedals. Figs. 4 and 5 are transverse sectional elevations of the clutch mechanism on the line *x x* of Fig. 6, showing the parts in and out of action. Fig. 6 is a cross-section on the line *y y* of Fig. 4. Fig. 7 is a longitudinal section through the combined tool-box and housing for the guide-pulley. Fig. 8 is a rear elevation of the same. Fig. 9 is a side elevation, partly in section, showing the manner in which the guide-pulley is applied to machines having a forward swiveled driving-wheel.

Referring to Fig. 1, A represents the main or driving wheel of the Star machine; B, the main frame in which the wheel is mounted; C, the front steering-wheel; D, the swiveling bar by which the steering-wheel is carried and controlled; E, one of the drums revolving loosely on the axle of the main wheel, and provided with the internal clutch mechanism for communicating motion thereto. This clutch mechanism is constructed of the ordinary type, or of the form hereinafter explained; F, one of the pedals or foot-levers; G, the flexible strap or band extending from the foot-lever to the forward side of the drum and wound backward around the latter for the purpose of imparting a forward rotation thereto when the pedal is depressed.

The levers, straps, and drums are arranged in duplicate on the two sides of the machine, and, with the exception of the peculiarities hereinafter explained, they may be constructed and arranged in the same manner, as in the machines now in common use.

In applying my improvements I omit from the interior of the driving-drum a spring commonly employed for effecting its backward rotation, and in lieu thereof I employ a flexible cord, chain, strap, or other flexible connection, H, passing over the pulley I, or other proper guides at the top of the main frame, and extending thence downward from opposite sides of the main wheels to the respective drums, around which its ends are wound from the forward side, as plainly shown in the drawings. The arrangement is such that the depression of either lever causes a forward rotation of the adjacent drum, also causing the latter to draw down the attached end of the cord H,

the opposite end of which is thereby unwound from the opposite drum, turning the latter backward and lifting the second pedal. It will be observed that the cord H serves not only to effect the positive backward rotation of the drum as the opposite drum is turned forward, but it also acts, through the drums and straps D, as a connection between the two pedals, causing one to rise as the other is depressed, and preventing them from both descending at one time. Under this connection the weight applied to either pedal may be counterbalanced by weight applied to the other, and thus the rider is relieved of the labor of lifting the weight of his legs after the downstroke and enabled to place his entire weight at will upon the two pedals for purposes of coasting. It will be seen that in this manner the rider is enabled not only to remove his entire weight, if desired, from the saddle in coasting, but also to carry his weight principally on his feet in propelling the machine, thus giving the present style of machines that ease of action which is so well understood in connection with the ordinary crank-machine.

In order to permit the employment of connections which are sufficiently strong and flexible without rendering them unnecessarily large, and to avoid the necessity which would otherwise arise of increasing the weight of the drums, I adopt the arrangement represented in Fig. 3, making use of a single connecting-cord, H, which winds upon the middle of the drum, and of two connecting-cords, G, which wind on sides of the drum. I prefer to make use of steel or other metallic cord consisting of fine strands of wire twisted or braided together.

Instead of using two separate cords doubled at the middle, as plainly represented in Fig. 40 3, the ends of the cords may be attached to the drum in any proper manner; but I recommend as a satisfactory device for the purpose a metal clip—such as shown at a in Fig. 3—its upper edge being doubled to form a V-shaped socket to hold the end of the cord H, while its lower edge is provided with a lip, c, to receive the cord G.

In order to prevent interference of the cords to guide them accurately to their places, and 50 to support them in such manner as to prevent unequal wear, I prefer to provide the drums with peripheral grooves therefor, as shown in the drawings; but it is to be understood that these grooves are not a necessary feature. It is also to be understood that while I prefer to 55 make use of the rounded cord, as shown in the drawings, flat straps of leather, metal, or woven material, or straps of other forms in cross-section, or metal chains or connections of other form may be used.

The pulley I may be constructed in any appropriate form. I recommend the employment of a covering—such as shown at K, Figs. 1, 7, and 8—formed in one end of a stationary 60 tool-box secured to the top of the main frame immediately in rear of the seat. This box is

provided with a longitudinal slide, d, adapted to be drawn backward over the top of the pulley.

Referring now to the facile type of machine 70 represented in Fig. 2, A represents a driving-wheel, which in this instance is mounted in a fork swiveled in the forward end of a perch or backbone, which carries a small trailing-wheel at the rear end, the general arrangement 75 being identical with that of ordinary crank-machines.

E represents the foot-levers, pivoted at their forward ends to the downward and forward extensions of the steering-fork and connected by 80 straps or cords G with the driving-drums E. These drums are mounted loosely on the axle and connected with the main wheel by a clutch mechanism, and are connected with each other by a cord, H, passing over the guide-pulley at 85 the top of the fork I. The arrangement of the drums and connections are identical with that in the first-described form of machine, and needs therefore no explanation. In this form of machine I propose to mount the guide-pulley 90 on the brake-supporting stud, which extends forward from the front of the fork, as usual, the stud being enlarged and elongated, in order to extend through the pulley and receive the brake at its forward end, as shown 95 in detail in Fig. 9.

While I have represented my improvements as applied to two of the leading forms of machines, it is to be understood that they may be employed in like manner in all the leading 100 machines in which levers and driving-clutches are employed on opposite sides, the only requirement being that the guide-pulley will be so located that the connecting-cord G will not interfere with the actions of the rider or the 105 other moving parts.

While I have represented but two cords passing from the drums to each pedal, it is to be understood that four or more may be employed, provided they are divided and separated in such manner as to admit the connecting-cord H between them, and instead of a single cord, H, two or more cords may be employed. The application of the pedal-cords to the two edges of the pulley, instead of the one 115 edge, is advantageous in that it avoids the side strain and friction which would occur if the pedal-cords were arranged to pull downward on one edge while the connecting-cord would pull upward on the opposite edge. 120

Passing now to the construction of the clutch mechanism for imparting motion from the drums to the wheel, attention is directed to Figs. 4, 5, and 6, in which f represents the axle fixed to the wheel g, a pulley keyed firmly to 125 the ends of the axle, its outer edge notched to receive a number of peripheral pawls or dogs, h, which are dovetailed or otherwise secured thereto in such manner as to slide outward and inward, their outer edges being provided 130 with ratchet-teeth adapted to engage corresponding teeth formed on the interior of the

surrounding pawl or drum E. The dogs may slide inward and outward at any appropriate angle to a radial line, the only requirement being that they should be adapted to engage 5 and disengage the teeth of the drum by their to-and-fro movements.

To the series of dogs I connect, by screws *i*, or in any other appropriate manner a ring, *k*, which is acted upon by one or more frictional plates, *l*, seated in the hub and urged downward by means of spiral springs *m*. These friction devices tend to turn the ring forward and backward with the drum, and the ring in turn, acting upon the dogs, causes them 15 to slide inward and outward with reference to their carrying-pulleys *G*. When the drum is turned forward, the friction devices turn the ring ahead, and the result is that the dogs are forced outward into engagement with the teeth 20 of the drum, as shown in Fig. 4, thereby locking the drum rigidly to the wheel, which is compelled to turn forward therewith, when the reverse movement of the drum causes the friction devices to urge the ring backward, 25 causing it to retract the dogs, so that the drum and the main wheel may revolve independently of the pulley and axle in a noiseless manner.

While it is preferred to employ the spiral 30 springs *m*, and to confine them, as shown in the drawings, by a tubular nut inserted through the side of the frame, it is to be understood that friction-springs of any other appropriate form may be employed to act upon the dog- 35 controlling ring.

In order that the dogs may be locked out of 40 action, to admit of the machine being rolled forward and backward at will, I propose to apply to the side of the pulley *g* a pivotal spring-finger, *o*, having at one end a stud which 45 may be seated in a hole in one of the dogs when the latter is retracted, as plainly shown in Figs. 6 and 10.

Having thus described my invention, what I 45 claim is—

1. In a bicycle or similar vehicle, the combination, substantially as shown, of the driving-wheel, the two driving-drums connected therewith by clutch mechanism, the flexible 50 cord or connection *H*, passing over an intermediate pulley and attached at its two ends to the respective drums midway between their

edges, the foot-levers arranged one adjacent to each drum, and two cords, *G*, connected with each foot-lever and extending thence to 55 the adjacent drum on opposite sides of the cord *H*, whereby side strains upon the drums are prevented and their tendency to tip side-wise avoided.

2. In a bicycle, the combination of the 60 wheeled driving-drums *E*, each provided with three peripheral grooves, the connecting-cord *H*, passed over an intermediate pulley and seated in the middle grooves of the drums, the foot-levers, and the cords *G*, extending 65 two from each lever to the outer grooves of the adjacent drum.

3. In combination with the driving-drum and the foot-lever for operating the same, the operating-cord *G*, doubled upon itself and secured to the plate *a*, connecting the cord at 70 its middle with the drum, whereby the cord is secured in position and its two ends separated to admit the intermediate cord.

4. In combination with the independently- 75 revolving internally-toothed drum, the pulley *G*, having peripheral notches therein, the toothed driving-dogs carried thereby, the ring connected to the dogs, and the frictional devices applied to the drum and acting upon 80 the ring, substantially as shown.

5. In combination with the driving-drum *D*, toothed internally, the internal driving-pulley, *G*, provided with peripheral notches, and the toothed dogs secured in said notches 85 by a sliding connection and adapted to slide into and out of engagement with the teeth of the drum, as described.

6. In combination with the drum, the movable dogs to engage the same, and the ring to 90 control the dogs, the friction-plate *l*, the spiral springs *m*, and the external nut to confine said springs.

7. In combination with the movable dogs and their connecting-ring, the latch *o*, whereby 95 the dogs may be held out of engagement.

In testimony whereof I have hereunto set my hand this 9th day of October, 1885, in the presence of two attesting witnesses.

WILLARD G. RICH.
